US0D1062402S

(12) **United States Design Patent** (10) **Patent No.:** **US D1,062,402 S**
(45) **Date of Patent:** **** Feb. 18, 2025**

(54) **LUNCH BOX**

(71) Applicant: **Zhongshan Kexinda Electrical Co., Ltd.**, Zhongshan (CN)

(72) Inventor: **Qinjun Huang**, Zhongshan (CN)

(73) Assignee: **Zhongshan Kexinda Electrical Co., Ltd.**, Zhongshan (CN)

(**) Term: **15 Years**

(21) Appl. No.: **29/898,294**

(22) Filed: **Jul. 25, 2023**

(51) LOC (15) Cl. **07-02**

(52) U.S. Cl.

USPC **D7/709**

(58) **Field of Classification Search**

(57) **CLAIM**

The ornamental design for a lunch box, as shown and described.

DESCRIPTION

FIG. 1 is a front perspective view of a lunch box, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is its split state diagram;

FIG. 10 is its split state diagram;

FIG. 11 is an enlarged detail view of area 11 in FIG. 2; and,

FIG. 12 is an enlarged detail view of area 12 in FIG. 4.

The broken lines in the drawings illustrate the portions of the lunch box, which form no part of the claimed design.

The dash-dot-dash broken lines encircling the enlarged views are for annotative purposes only and form no part of the claim thereof.

1 Claim, 12 Drawing Sheets
